UNITED STATES PATENT OFFICE.

HERBERT E. VAN DORN, OF CHICAGO, ILLINOIS.

METAL END CONSTRUCTION FOR FREIGHT CARS.

1,412,072.

Specification of Letters Patent. Patented Apr. 11, 1922.

Application filed June 7, 1920. Serial No. 386,998.

To all whom it may concern:

Be it known that I, HERBERT E. VAN DORN, a citizen of the United States, residing at Chicago, county of Cook, State of Illinois, have invented a certain new and useful Improvement in Metal End Constructions for Freight Cars, and declare the following to be a full, clear, and exact description of the same, such as will enable others skilled in the art to which it pertains to make and use the same, reference being had to the accompanying drawings, which form a part of this specification.

My invention relates to the provision of means for strengthening and bracing the body portion, particularly the ends thereof, of car bodies. These end portions of the body are subjected to much greater strains than the side portions, abnormal pressure, shocks and blows frequently arising internally due to the shifting of the cargo, and externally from some other source, such for instance as a collision between the adjoining ends of two cars. To protect these body ends, it has been the practice to provide the ends of the car with so-called metal end plates but it has been found that these plates, usually supported mainly from the usual main frame of the car, are not sufficiently stable at the roof portion of the car to withstand the above mentioned abnormal pressure. I have provided a series of metal braces for properly trussing the upper portion of a metal end plate of a car body and the adjacent end portion of the roof frame.

In the drawings:

Figure 1 is a top plan view of the end portion of a car, with the roof removed; and Figs. 2, 3 and 4 are similar views showing variations in the particular form and arrangement of parts.

In carrying out the invention, in Fig. 1, A—A' represent the usual longitudinal main frame members or side plates that support the roof; B—B' the usual vertical corner posts; and C—C' the usual wood end pieces of the body. D is a sheet metal end, extending preferably from floor to roof of the car, having vertical end flanges, d. E—E' are the usual wood sheathing constituting the outer side walls of the body.

F are two wooden strips extending across the upper portion of the car from one roof

main frame member, A, to the other member, A'.

G is a metal strip, flanged at its ends as at g—g'. H is a metal strip located outside the wall, E, of the body and J is another metal strip located on the inner face of the member A. The flange, g, of the plate G, the strip H, and the strip J are engaged together, preferably by bolts, j, and through the member A so as to bind them all tightly and compactly.

The opposite side of the structure is similar to that just described, the flange, g', plate H' and plate J' being bolted together through the member A' by bolts j'.

K is a metal strip flanged at its ends as at k—k', the latter being bolted respectively to the frame members A—A' and plates J—J' by the bolts, k'. The flat portion K², of the strip K is bound to the plate G, strips F, strips C—C' and end D by bolts or rods, K³.

In Fig. 2 the form of the bracing is varied. Between the cross pieces, C—C', cross pieces, F, and longitudinal upper frame members, A—A' is located a metal brace, L, the respective ends, l, thereof being bound to the members A—A' by the bolts, l'. L' is a plate of angle iron shape in cross section and the vertical flange of same is bound by the bolts, l'', to the flat portion, l³, of the member L and the plates F. L² is a similar angle iron plate, similarly bound to the portion, l⁴, of the member L, the plates C—C' and the sheet metal end D. L³ are crossed metal straps each having its respective ends bound to the horizontal flanges, l⁵, of the plates L'—L² respectively.

Figure 3 shows, instead of the form of the brace member L (Fig. 2) a brace member, M, having a flattened middle portion, m, and flattened end portions, m'. M' are metal members of angular shape in cross section, the upright flange of one being bolted through the portion m to the plates, F, by the bolts m², while the upright flange of the other angle plate M' is bolted through the strips C—C', to the sheet metal end, D. N—N' are angle iron plates adapted to fit the respective corners at the upright posts, N², of the main frame and one flange of each of these angle pieces is bolted respectively through the flange, m', of the brace, M, through the longitudinal members A—A' and through plates, N³. O is a metal strip,

preferably angle iron shaped in cross section, and engages at each end the brace, M. O are crossed braces engaged together at o and to the cross piece O and engaged at each 5 end to horizontal flanges of the plates M'.

Fig. 4 shows a still further variation in the arrangement of the brace members. P is a metal strip, preferably angle iron shaped in cross section, flanged at its ends, p. P' are 10 outer metal plates having their ends flanged as at p' to embrace the flanged ends, d, of the sheet metal end, D, and also to embrace the vertical frame post, N². Q are inner metal straps or plates. Fastening bolts, q, 15 pass through plates, P' the longitudinal main roof frames, A—A', and the plates Q, the flanges, p', of the plates, P', being bound to the sheet metal end, D, and strips, C—C' by the bolt formation end, q' of the plates 20 Q. R is a cross strip or brace engaged at each end respectively to a corner of the piece P and S are longitudinal brace members crossed and engaged together, as at s, and having the respective ends engaged to 25 gusset plates, S', and the metal plate, S², which is bolted to the end pieces C—C' and sheet metal end, D, as at s'.

What I claim is:

1. The combination with the frame of a 30 car body including longitudinal upper side members, of a metal end engaged to one end of said frame, and a reinforcing truss extending between said side members in opera-

tive relation to said metal end, said truss including a piece having a central section 35 extending parallel to said metal end and end sections extending from said middle section diagonally toward said side frame members and approaching said metal end, the outer ends of said end sections being secured to 40 said side frame members, together with pieces extending longitudinally between the middle section of said piece and the middle of the upper end of said metal end.

2. The combination with the frame of a 45 car body including longitudinal upper side members, of a metal end engaged to one end of said frame, and a reinforcing truss 50 extending between said side members in operative relation to said metal end, said truss including a piece having a central section 55 extending parallel to said metal end and end sections extending from said middle section diagonally toward said side frame members and approaching said metal end, the outer 60 ends of said end sections being secured to said side frame members, together with pieces extending longitudinally between the middle section of said piece and the middle of the upper end of said metal end, said longitudinal pieces crossing each other between the ends thereof.

In testimony whereof, I sign this specification.

HERBERT E. VAN DORN.
